[57] CLAIM

The ornamental design for an automobile floor mat, as shown and described.

DESCRIPTION

FIG. 1 is a top plan view of an automobile floor mat showing our new design;

FIG. 2 is a left side elevation view thereof, it being understood that the right side is a mirror image of that shown;

FIG. 3 is a lower end elevation view thereof;

FIG. 4 is a bottom plan view thereof; and

FIG. 5 is an enlarged fragmentary cross section view taken along line 5—5 in FIG. 1.

FIG. 1

FIG. 2

FIG. 3

FIG. 5

FIG. 4
